DESIGN FOR A LADY'S SLIP

Samuel J. Dichter, New York, N. Y.

Application October 29, 1937, Serial No. 72,499

Term of patent 14 years

To all whom it may concern:

Be it known that I, Samuel J. Dichter, a citizen of the United States of America and resident of the county of New York, city and State of New York, have invented a new, original, and ornamental Design for a Lady's Slip, of which the following is a specification, reference being had to the accompanying drawing forming a part thereof.

In the drawing:

Figure 1 is a front view of a lady's slip embodying my design.

Figure 2 is a back view thereof.

Figure 3 is a right side view of Figure 2.

The characteristic feature of my design resides in the particular stitching on the front and back of the slip in combination with the specific slip, as shown.

I claim:

The ornamental design for a lady's slip as shown and described.

SAMUEL J. DICHTER.
